UNITED STATES PATENT OFFICE.

RUDOLF CARL, OF SCHMARGENDORF, NEAR BERLIN, GERMANY, ASSIGNOR TO SIEMENS & HALSKE, A. G., OF BERLIN, GERMANY, A CORPORATION OF GERMANY.

MEANS FOR CAUSING MERCURY TO CIRCULATE WHILE ELECTROLYZING AQUEOUS SOLUTIONS OF METALLIC SALTS.

1,025,509.

Specification of Letters Patent.

Patented May 7, 1912.

Application filed October 24, 1911. Serial No. 656,506.

To all whom it may concern:

Be it known that I, RUDOLF CARL, a subject of the Emperor of Austria-Hungary, and residing at Schmargendorf, near Berlin, Germany, have invented certain new and useful Improvements in Means for Causing Mercury to Circulate While Electrolyzing Aqueous Solutions of Metallic Salts, of which the following is a specification.

My invention relates to the circulation of mercury when electrolyzing aqueous solutions of metallic salts.

When electrolyzing aqueous solutions of metallic salts by means of a mercury cathode, *e. g.* in the chlorin-alkali electrolytic process, as is well-known the uniform and uninterrupted movement of the mercury is of great importance. In the processes customary at the present day the mercury is preferably conveyed by mechanical means, but large quantities of mercury are then requisite.

A primary object of my invention is to produce a circulation of the mercury by means of the action of heat. To this end, I arrange the mercury in a hydrostatically closed ring for example, by connecting the two sides of a cell by a pipe. For bringing about the circulation I produce differences of temperature in the ring of mercury either by cooling the mercury at one place, or by supplying heat to another place, or by using both means simultaneously. The mercury at the place subjected to a higher temperature is expanded and is contracted at the part of lower temperature, whereby a uniform circulation is produced in the hydrostatically closed ring. The mercury is preferably cooled in proximity to the outlet of the cell and heated in proximity to the inlet. The cooling may be brought about by any cooling agent, *e. g.* water, within or without the cell, and the heating by special heating means of any kind in the event of the heat occurring during the electrolysis not sufficing.

In carrying the process into practice only small quantities of metal are required; a layer about 5 mm. deep on the bottom of

the cell suffices. Also, the amount of energy requisite for producing the circulation is exceedingly small as the mercury is in hydrostatic equilibrium and a disturbance of this equilibrium, *i. e.* circulation, occurs owing to a very slight change in the temperature conditions.

One illustrative embodiment of the invention is represented by way of example in the accompanying drawing in vertical sectional elevation.

Referring to the drawing, *a* designates a cell containing mercury *b* on the bottom thereof. The two sides of the cell are connected with one another by a pipe *c*. The arrows indicate the direction in which the mercury circulates.

d designates heating means and *e* cooling means.

The remaining parts of the plant are non-essential to the understanding of the invention and have therefore been omitted for the sake of clearness. The hydrostatically closed ring may of course include a plurality of cells.

I claim:

1. In a plant for electrolyzing aqueous solutions of metallic salts, the combination with a cell containing mercury of a hydrostatically closed mercury ring connected with said cell, and means for producing differences of temperature in the mercury in the ring near the points of connection.

2. In a plant for electrolyzing aqueous solutions of metallic salts, the combination with a cell containing mercury, of a pipe connecting two sides of the cell below the level of the mercury, and means for cooling the mercury in the pipe near one side of the cell.

3. In a plant for electrolyzing aqueous solutions of metallic salts, the combination with a cell containing mercury, of a hydrostatically closed pipe connecting two sides of the cell below the level of the mercury, and means for heating the mercury in the pipe near one side of the cell.

4. In a plant for electrolyzing aqueous solutions of metallic salts, the combination with a cell containing mercury, of a pipe

connected with two opposite sides of the cell below the level of the mercury, cooling means for cooling the mercury in the pipe near one side of the cell, and heating means 5 for heating mercury in the pipe near the other side of the cell.

In testimony whereof, I have signed my

name to this specification in the presence of two witnesses.

RUDOLF CARL.
